United States Patent

Des. 238,350

Patented Jan. 6, 1976

238,350

TRUCK BODY

John Riate, Lynwood, and Sheldon T. Schreiber, Palos Verdes Peninsula, Calif., assignors to SSP Truck Equipment, Inc.

Filed Jan. 23, 1975, Ser. No. 543,272

Term of patent 14 years

Int. Cl. D12—08

U.S. Cl. D12—98

FIG. 2

FIG. 3.

FIG. 4.

FIG. 5.

FIG. 6.

FIG. 7.

FIG. 1 is a perspective view of a truck body showing our new design.

FIG. 2 is a top plan view thereof.

FIG. 3 is a side elevational view thereof.

FIG. 4 is a front end elevational view thereof.

FIG. 5 is a rear end elevational view thereof.

FIG. 6 is a perspective view thereof with the top tray cover of one side in open condition.

FIG. 7 is a side elevational view of a truck body showing a second embodiment of our new design wherein the only difference resides in the side panel which is of three sections.

We claim:

The ornamental design for a truck body, substantially as shown and described.
